Primary Examiner—Catherine Tuttle[57]*CLAIM

The ornamental design for a shampoo bar with string and hook fastener, as shown and described.

DESCRIPTION

In FIGS. 1 and 2 the broken line showing of the word "shampoo" is for illustrative purposes only and forms no part of the claimed design.

FIG. 1 is a front elevational view of the shampoo bar with string and hook fastener showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.
